UNITED STATES PATENT OFFICE.

THEODOR REIS, OF CINCINNATI, OHIO.

RIVETING DEVICE.

1,152,971.

Specification of Letters Patent. Patented Sept. 7, 1915.

Application filed June 5, 1914. Serial No. 843,293.

To all whom it may concern:

Be it known that I, THEODOR REIS, residing at Cincinnati, Hamilton county, State of Ohio, have invented a certain new and 5 useful Riveting Device, of which the following is a clear, full, and exact description, attention being called to the drawing, which accompanies this application and forms a part thereof.

10 This invention concerns a device to be used in connection with riveting sheet metal. The particular functions which this device is intended to perform consist of positioning the rivet, of forcing it through the 15 metal and of holding a tool, a so called "set", in proper position for forming the head, this being done by means of a hammer.

15 The invention consists of the construction of such a device as hereinafter described and claimed and as illustrated in the accompanying drawing, in which—

20 Figure 1. shows the device in side elevation with parts in normal position, that is, at rest. Fig. 2. is a top view of the same. Fig. 3. is a horizontal section of it on line 25 3—3 of Fig. 1. Fig. 4. shows the rear end of it. Fig. 5. on enlarged scale shows portions of Fig. 1 with certain operating parts in alternate positions. Figs. 6 and 7 in 30 similar views show other operating parts in their respective alternate positions.

25 Letter A indicates a bench or other suitable support upon which the device is mounted.

30 B indicates the frame of the device provided with flanges b for its attachment.

35 Numeral 7 indicates the anvil upon which the work is supported and riveted. This anvil may preferably form a part of the 40 frame as shown. It is provided with a pocket 8 which at the beginning of an operation contains a rivet 9. A punch or plunger 10 is contained in the lower part of this pocket and adapted to vertically traverse 45 the same so as to expel the rivet contained therein.

45 11 indicates a counter-sunk die supported in axial alinement above punch 10 and capable of moving toward and from the mouth 50 of pocket 8, being guided accordingly in an overhanging part of the frame which is shaped to form an arm 12.

13 is a tubular guide for the tool whereby the rivet head is formed, this tool, also called "set", being indicated by numeral 14. 55 This set is snugly contained in guide 13 with a sliding fit, an enlargement or head 15 being provided at its upper end which prevents it from dropping out of the guide. This latter is fitted to arm 12 of the frame 60 so as to be capable of a vertical movement with respect to anvil 7.

16—16 indicates two pieces of sheet-metal to be riveted to each other.

65 In using this device plunger 10 and die 11 are caused to act first for the purpose of forcing a rivet through the superposed pieces of metal and for seating it therein as shown in Fig. 5, preparatory to being riveted. These pieces of metal rest at that time 70 above rivet pocket 8 which latter contains a rivet in inverted position, that is, shank up. The metal with the inserted rivet is now moved so that this latter is below set 14 as shown in Fig. 6, after which the rivet is set, 75 that is its head is being formed by means of hammer-blows delivered upon enlargement 15 of the set which enlargement serves as a driving-head. While this is being done, the superposed pieces of sheet-metal are held in 80 close contact around the shank of the rivet by means of guide 13 the lower annular edge of which is pressed upon them as shown in Fig. 7.

85 The means for actuating these working parts are as follows: Die 11 is moved by a lever 17 pivotally supported at 18. Punch 10 is moved by a lever 19 pivotally supported at 21. A spring 20 acts at the ends 90 of these levers in a manner to hold the working parts connected therewith in normal, that is, inoperative positions. These levers are operated by a cam C mounted upon a shaft 22 supported in the frame. The cam is actuated, as shown in dotted 95 lines, by an arm 23 mounted upon shaft 22. A manipulating lever 24, preferably in form of a treadle serves for the purpose, it being connected to arm 23 by means of a link 25. The action on this lever is against a spring 100 26 which holds the parts in normal position. Cam C is so shaped and positioned that by means of its part 27, it acts upon lever 17 first, the object being to move die 11 into

position upon the sheet metal so as to hold the same against the action of punch 10 before this latter starts to act.

Action upon lever 24 being continued, lever 19 will be actuated in due time so as to move punch 10 against the rivet, this being by the part 28 of the cam. No further action is transmitted at that time by the cam to lever 17, the latter remaining in position 10 for holding the die in place while the punch forces the rivet through the metal. Lever 24 is released now and permits spring 26 to restore it and cam C to their respective normal positions. The metal with the inserted 15 rivet is now shifted so that the upturned shank of the rivet is below the lower end of set 14, this latter being slowly lowered thus serving as a pointer to enable the operator to properly position the rivet. The position 20 of the parts which results from this manipulation is shown in Fig. 6 and as to set 14 is due to action on a lever 29 operatively connected to guide 13 which carries said set. This action is obtained by means of a manipulating lever 31 preferably in form of a treadle supported at 32 and connected by 25 means of a link 33 to lever 29. The work with the inserted rivet having thus been positioned, action against lever 31 proceeds, 30 whereby guide 13 is caused to continue to move in the same direction but alone, the set remaining in position on the end of the rivet. The position resulting from this manipulation is illustrated in Fig. 7, head 15 of the 35 set being clear above guide 13. The rivet is now set, that is the additional or finishing head is formed by means of hammer-blows delivered upon driving-head 15 of the set. While this is being done, pressure on lever 40 31 is maintained so as to obtain the action of the lower end of guide 13 as shown in Fig. 7 for the purpose of holding the superposed pieces of sheet-metal in close contact all around the shank of the rivet until the 45 connection of this latter is completed. The action is against a spring 34 which, by bearing against said lever 31, returns these parts to their respective normal positions after the rivet is clenched.

50 With a view to simplification, lever 29 is mounted upon pivot 18 which also supports lever 17 and to render this possible in a practical manner part of this lever is bent or bail-shaped as best shown in Fig. 2 which 55 permits the two opposite parts of this bail-shaped portion to be mounted upon the ends of pivot 18 with guide 13 supported between them. One of these parts of this bail-shaped portion is continued rearwardly for connection to link 33.

The rivets may be inserted in pocket 8 from the top, one at the time as needed, or they may be fed in through a slotted passage 35 which is laterally open as shown in Fig. 6. Metal abraded or sheared off by the riv-

ets while being forced upwardly through the metal by punch 10 may clear through a vent-opening 36 in die 11.

Sheet metal work, where small pieces like handles for instance are connected, involves 70 considerable riveting with use of a limited number of rivets per connection, the rivets being usually equally spaced. The distance between set 14 and die 11 may be arranged to equal this space and if this is done, work 75 of this character may be formed quite expeditiously by means of this device because after the first rivet is placed by the punch, the subsequent positioning of this rivet below the set for forming its head also aids in 80 placing the work in position for receiving the next rivet. Observe Fig. 6.

Having described my invention, I claim as new:

1. In a device of the kind described, the 85 combination of a pivot, a frame in which it is supported, two operating levers mounted on this pivot, a rivet-set connected for operation to one of these levers, a countersunk die connected for operation to the other 90 lever, a punch adapted to co-act with the die mentioned, an operating lever for it and means to actuate all these levers.

2. In a device of the kind described, the 95 combination of an anvil for supporting sheet metal to be riveted, a rivet pocket provided in said anvil, a punch movably supported in this pocket, a countersunk die movably supported opposite the rivet pocket and in axial alignment therewith, means to move this die 100 in contact with the sheet metal while positioned above the rivet pocket and means to move the punch toward the die so as to force a rivet into the sheet metal.

3. In a device of the kind described, the 105 combination of a support for the sheet metal, complementary rivet-inserting members consisting of a countersunk die and of a punch adapted to co-act therewith, an actuating lever for each of these members adapted to operate them so that the die is first moved upon the sheet metal from one side after which the punch is moved against the other side for the purpose of inserting a rivet, a 110 cam whereby these levers are moved in the manner set forth, and means to actuate this cam.

4. In a device of the kind described, the 115 combination of a frame comprising an anvil adapted to support sheet metal to be connected, a countersunk die and a rivet-set positioned above the anvil, a lever to actuate each, a pivot supported in the frame on which these levers are mounted, a punch positioned below the countersunk die and 120 adapted to co-act therewith, a lever to actuate it and means to operate each of these levers.

5. In a device of the kind described, the 125 combination of a frame comprising an anvil 130

adapted to support sheet metal to be connected, a countersunk die and a punch adapted to co-act therewith for the purpose of inserting a rivet into the sheet metal, a lever to actuate each of these parts supported in the frame mentioned, a rivet-set for clinching the inserted rivet, a lever to actuate it also supported in the frame men-

tioned and means to operate each of these levers.

In testimony whereof, I hereunto affix my signature in the presence of two witnesses.

THEODOR REIS.
